UNITED STATES PATENT OFFICE.

LEBRECHT J. KLUG, OF MILWAUKEE, WISCONSIN, ASSIGNOR TO KLUG & SMITH COMPANY, OF MILWAUKEE, WISCONSIN, A CORPORATION OF WISCONSIN.

DESIGN FOR A TRAFFIC-REGULATOR SIGNAL CASING.

Application filed April 13, 1923. Serial No. 5,808. Term of patent 7 years.

To all whom it may concern:

Be it known that I, LEBRECHT J. KLUG, a citizen of the United States, and a resident of Milwaukee, county of Milwaukee, and State of Wisconsin, have invented a new, original, and ornamental Design for Traffic-Regulator Signal Casing, of which the following is a specification, reference being had to the accompanying drawing, forming a part thereof.

I claim:

The ornamental design for a traffic regulator signal casing, substantially as shown.

LEBRECHT J. KLUG.
